Primary Examiner — Melanie H Tung*Assistant Examiner* — Bao-Yen Nguyen(74) *Attorney, Agent, or Firm* — NSIP Law(57) **CLAIM**

We claim the ornamental design for a display screen or portion thereof with graphical user interface, as shown and described.

DESCRIPTION

FIG. 1 is a front view of a display screen or portion thereof with graphical user interface showing our new design; and, FIG. 2 is an enlarged front view thereof, but shown without the broken lines for clarity of illustration. The outer broken lines in FIG. 1 show the display screen or portion thereof and the other broken lines in FIG. 1 represent portions of the graphical user interface; the broken lines form no part of the claimed design.
